UNITED STATES PATENT OFFICE.

GEORGES LAMOUREUX, OF PUTEAUX, FRANCE.

CARBURETOR.

Application filed December 1, 1922, Serial No. 604,365, and in France December 6, 1921.

The present invention relates to an improved spray carburetor embodying a jet nozzle delivering automatically the quantity of liquid fuel required for the various speeds 5 of the engine.

It is a well known fact that spray carburetors generally possess the disadvantage that, in proportion as the speed of the engine increases, the depression in the carburetor 10 due to the engine suction likewise increases, and the liquid fuel is injected in a greater proportion relatively to the air, giving a richer explosive mixture.

It has heretofore been proposed to provide 15 a carburetor wherein the liquid fuel enters the same through a calibrated hole in the lower part of a tube, which latter is pierced along its length with holes communicating with the atmosphere. This tube, moreover, 20 is pierced adjacent its upper end with a great number of holes for the exit of the air and fuel. During the normal running of an engine provided with this type of carburetor, no liquid level can be formed in the tube 25 and the sprayed fuel is delivered as a jet and is mingled with the air entering through the compensating hole. The constant value 30 of the mixture is automatically regulated only during the resumption of speed.

An object of the present invention is to 35 provide a carburetor which automatically corrects or regulates the mixture not only during the resumption of speed but during the normal running, which automatic control 40 results primarily from the formation of a level of liquid fuel within a central tube at all times.

The carburetor of the present invention is 45 characterized by the fact that a central tube is supplied with liquid fuel by a calibrated opening at its lower end, and the fuel and air mixture evolved in the carburetor is delivered through a calibrated opening at the upper part of said tube, the two openings being analogous.

The following description with respect to 50 the accompanying drawing, giving an example of the invention, describes the practical realization thereof and will give a clear idea of its special features and advantages.

The single figure is a diagram of the carburetor in section made axially of the sprayer.

The body of the carburetor is designated 55 by a , its butterfly or throttle valve by a^1

the constant level is at b and the aperture of the sprayer at c , this aperture being situated at the upper part of a connecting tube d , the base of which connects with the fuel supply pipe e .

The communication between these two parts d and e is established by means of an aperture f similar to that represented at c , i. e. capable of passing the same quantity of liquid under the same pressure or depression. Around the tube d and communicating with it by a certain number of holes g , in the wall of this latter, there is a concentric tube or sleeve h , closed at the lower part and open at its upper edge, which is practically as high 60 as the natural level of the liquid fuel. A third concentric tube i surrounds the tube h , and opens in a medium not subject to the suction of the engine, for instance at the base of the carburetor, where apertures j are 65 provided.

Finally, a system of heating by exhaust water or gas such as that indicated, for instance, at k , may be arranged in order to complete the whole device.

In order to explain the working of this system, one must first of all consider the conditions in which the tube d is found, viz, that it is provided with balanced apertures 80 at its base and at its summit. The suction which is exerted at the upper aperture c , tends to make it deliver immediately, but this suction not acting instantaneously on the aperture f , in the neighborhood of which the liquid is approximately in equilibrium, no 85 discharge is produced at f to begin with. This discharge can only take place by a diminution of pressure at the base of the tube d by a fall in the level of the liquid therein. The aperture f will thus have a retarding influence on the aperture c , when the suction in the carburetor is increased, and this will tend to empty the tube d , and will bring about the injections of air into the said tube 90 by the sleeves h , i .

By reason of the holes g , the space between d and h , will be full when at rest and when the engine is running slowly, as indicated in the drawing, and all the holes will be submerged and the sprayer will deliver pure fuel in a full jet. But if the speed of the engine is accelerated, the depression due to the suction makes itself felt immediately and, as the atmospheric pressure acts as indicated by the arrows f^1 , f^2 , 100 105 110

in the space between d and h , the fuel level will go down, uncovering a certain number of apertures g , and there will be then an admission of air which will mix with the fuel before leaving the sprayer c .

The vacuum existing in this tube is smaller (which means that the pressure is greater) than if there had not been any admission of air, the spraying nozzle f will 10 consequently deliver less fuel as its delivery depends upon the difference of pressure between the atmospheric pressure acting in the float chamber and the vacuum in the tube d .

15 Moreover, the air entering into the tube d through the holes g occupies a certain volume and under these conditions the delivery of fuel of the spraying nozzle c will also be reduced. It will therefore be seen that the 20 admission of air into the tube d has for effect to reduce at the same time the delivery of fuel of the spraying nozzle f and the delivery of fuel of the spraying nozzle c . Accordingly, as the spraying holes f and c are 25 similar or balanced there will be at every moment a state of balance, that is to say a liquid level which will lower as the vacuum at a increases and the air entering into the central tube through the holes g will brake 30 or retard and diffuse the fuel to an extent corresponding to the increase in the vacuum. Consequently it will be possible to obtain an automatic correction for all the rates of 35 running.

40 The value of this correction will of course depend on the number, the section and the distribution of the holes for the passage of air, and these it will not be difficult to determine. Moreover, the fuel will be intimately mixed with air before it leaves the sprayer, and owing to this fact, a better utilization of the liquid fuel will be produced.

45 Variations in temperature may be corrected by a heating system applied around the sprayer nozzle.

What I claim is:

50 1. A carburetor with automatic regulation, comprising a central tube wherein a liquid fuel level is maintained during normal operation, a calibrated orifice at one end thereof communicating with the float chamber, air inlet holes provided in the central tube, a single orifice of substantially the same size as said first-named orifice formed at 55 the other end of the central tube, and means for bringing the external air at atmospheric

pressure to the air inlet holes of the central tube.

2. A carburetor with automatic regulation, comprising a central tube wherein a liquid fuel level is maintained during normal operation, a calibrated orifice at one end thereof communicating with the float chamber, air inlet holes provided in the central tube, a single calibrated orifice of analogous section relative to said first-named orifice formed at the other end of the central tube, a sleeve surrounding the central tube and having one end open, and means affording an atmospheric communication for the open end of the said sleeve. 60

65 3. A carburetor with automatic regulation, comprising a central tube, a calibrated orifice at one end thereof communicating with the float chamber, air inlet holes provided in the central tube, a single calibrated orifice of analogous section formed at the other end of the central tube, a sleeve surrounding the central tube and having one end open, a second sleeve surrounding the latter, communicating with the atmosphere by its open end and having the other end closed in such manner as to direct the outer air towards the air inlet hole of the central tube. 70

75 4. A carburetor with automatic regulation, comprising a central tube, a calibrated orifice at one end thereof communicating with the float chamber, air inlet holes provided in the central tube, a calibrated orifice having the same diameter as said first-named orifice formed at the other end of the central tube, a sleeve surrounding the central tube and having one end open, and means affording an atmospheric communication for the open end of the said sleeve. 80

85 5. A carburetor with automatic regulation, comprising a central tube, a calibrated orifice at one end thereof communicating with the float chamber, air inlet holes provided in the central tube, a single calibrated orifice of equal section formed at the other end of the central tube, a sleeve surrounding the central tube and having one end open, a second sleeve surrounding the latter, communicating with the atmosphere by its open end and having the other end closed in such manner as to direct the outer air towards the air inlet hole of the central tube. 90

95 In testimony whereof I have signed this specification.

GEORGES LAMOUREUX.
